United States Patent Office

Des. 210,943
Patented May 7, 1968

210,943

GRAVE COVER

Kenneth H. Reeson, Regina, Saskatchewan, Canada, assignor to Carolina Cemetery Services, Inc., Florence, S.C., a corporation of South Carolina

Filed Mar. 8, 1967, Ser. No. 6,118

Term of patent 7 years

(Cl. D19—1)

I claim:

The ornamental design for a grave cover, as shown and described.
